UNITED STATES PATENT OFFICE.

WILLIAM B. BROWN, OF GREENVILLE, SOUTH CAROLINA.

SELF-THREADING SHUTTLE.

1,356,513.

Specification of Letters Patent.

Patented Oct. 26, 1920.

Application filed February 25, 1920. Serial No. 361,199.

To all whom it may concern:

Be it known that I, WILLIAM B. BROWN, a citizen of the United States, residing at Greenville, in the county of Greenville and State of South Carolina, have invented certain new and useful Improvements in Self- Threading Shuttles; and I do hereby declare the following to be a full, clear, and exact description of the invention, such as will enable others skilled in the art to which it appertains to make and use the same.

The object of the invention is to provide a simple and effective self threading loom shuttle wherein the guiding of the yarn after the shuttle has been threaded may be effected without undue friction or chafing or the liability of displacement or disarrangement due to the ballooning of the yarn, and whereby the desired and necessary tension upon the yarn to prevent looseness or slack due to the run of the shuttle may be accurately adjusted without loss of time or the necessity for expert assistance other than that possessed by the ordinary loom operator, and with these objects in view the invention consists in a construction and combination of parts of which a preferred embodiment is shown in the accompanying drawings, wherein:

Figure 1 is a plan view of the shuttle provided with self threading means constructed in accordance with the invention.

Fig. 2 is a side view of the same.

Fig. 3 is a longitudinal section in the plane of the threading slot.

Figs. 4 and 5 are side views taken respectively from opposite sides of the block detached from the shuttle body.

Figs. 6 and 7 are end views taken respectively to show opposite ends of the block.

Fig. 8 is a transverse section taken on the plane indicated by the line 8—8 of Fig. 1, in the plane of the tension screw.

The threading device indicated generally at 10 is arranged in the forward end of the shuttle body 11 having the usual bobbin chamber 12 in which is arranged the bobbin 13, said self threading device consisting of a single block which is seated in a suitable cavity at the forward end of the bobbin chamber and is held in place by a transverse screw 14 located in rear of the delivery eye 15 of the shuttle body and countersunk below the bottom of the thread groove 16.

The block is provided with the longitudi-

nal thread guide 17 arranged substantially in alinement with the axis of the bobbin and accessible through a threading slot 18 formed longitudinally in the top of the block and opening into a longitudinal bore 19 which is almost closed at its bottom by a transverse deflector rib 20 serving to direct the yarn into the guide and overhanging the latter to minimize the possibility of the yarn leaving said guide after it has become seated therein.

One side of the block at its outer surface is extended to form a beak 21 which extends under an overhanging ear 22 between which the yarn must pass in the threading operation, and depending from said beak is the horn 23 terminating in a rearwardly directed toe 24 bounding the front side of the eye 25 which registers with the delivery eye of the shuttle body and is spanned by the snubbing pin 26 which extends terminally below the toe of the horn so that as the yarn is drawn downward after passing the beak, over the horn, it comes in contact with the snubbing pin and is directed into the eye of the block through which it is fed to the delivery eye of the shuttle. Guide or snubbing pins 27 and 28 may also be arranged at the front and rear sides of the delivery eye of the shuttle body, to relieve friction upon the yarn in passing therebetween in the forward and rearward runs of the shuttle.

Also at its inner or rear end (adjacent to the bobbin chamber) the block is provided with pliable fingers 30 for holding a friction pad 31 in position for traverse by the yarn in passing from the bobbin to the guide in the block.

Extended upward from the lower side of the block, in the body portion thereof and intersecting the yarn guide is a tension screw 32 having a longitudinal kerf 33 registering with the yarn guide and accessible through a lateral passage 34 which is overhung by a beveled deflector tip 35 corresponding substantially in section with the deflector rib which spans the space between the threading passage of the block and the yarn guide, to the end that as the yarn is drawn through the threading channel and downward toward the yarn guide, it is also deflected into the lateral passage formed in the tension screw to lie ultimately in the kerf in the tension screw, so that by turning the latter more or less the yarn guide may be choked.

more or less to apply the desired frictional resistance or tension to the yarn to regulate the feeding thereof through the guide.

What is claimed is:—

- 5 1. A self threading shuttle having a yarn guide and a communicating threading channel intercepted by a laterally extending beak and an overlapping ear, a horn depending from the beak and having a rearwardly directed forwardly convexed toe bounding an eye in registration with the delivery eye of the shuttle body and spanned by a snubbing pin extending beyond the extremity of said toe for engagement with and deflection of a strand of yarn traversing the surface of the toe.
- 10 2. A self threading shuttle having a threading block provided with a longitudinal yarn guide and a communicating threading channel and related means for directing the yarn to the delivery eye, and a tensioning device consisting of a revoluble member provided with a longitudinal kerf in communication with said yarn guide.
- 15 3. A self threading shuttle having a thread block provided with a yarn guide and a threading channel in communication therewith and means for directing the yarn from said channel to the delivery eye, and a tension screw spanning the yarn guide and provided with a kerf in registration therewith and revoluble to vary the position of the kerf relative to the run of the yarn.
- 20 4. A self threading shuttle having a threading block provided with a yarn guide and a communicating threading channel and

means for directing the yarn to the delivery eye, a deflector rib being disposed between the threading channel and the yarn guide, a tension screw disposed in and having a laterally accessible kerf in registration with the yarn guide, and a deflector tip disposed in registering relation with said deflector rib and overhanging said tension screw.

5. A self threading shuttle having its body provided with a delivery eye, a threading block having a longitudinal thread guide and a friction pad located at the entrance to said yarn guide, a threading channel extending longitudinally of the block and spanned at its forward end by a transversely projecting beak and an overlying guard ear, said threading channel being separated from the yarn guide by an overhanging deflector rib, a horn depending from the beak and having a rearwardly directed toe bounding the forward side of an eye in communication with the yarn guide, and a snubbing pin arranged in spanning relation with the said eye and spaced from the extremity of the toe and projecting terminally beyond the latter for intercepting the yarn in its passage around the horn to direct the same into the eye, in combination with means for transversely restricting the yarn guide at an intermediate portion of its length.

In testimony whereof I affix my signature in presence of two witnesses.

WILLIAM B. BROWN.
